ATOMIZING NOZZLE

Cedomir M. Sliepcevich, Ann Arbor, Mich., assignor to Kask Technical Corporation, Jackson Heights, N. Y., a corporation of New York

Application August 21, 1948, Serial No. 45,529

1 Claim. (Cl. 299—150)

1

The present invention relates to nozzles for atomizing liquids. Particularly in one aspect this invention relates to such a nozzle in which a vibrating member is employed to bring about the desired degree of atomization.

In the commercial atomizing nozzles on the market today in which pressure alone is employed as the atomizing force as contrasted with those in which a gas under pressure is used as the propelling and disruptive agency, the atomization of the liquid is produced by subjecting it to a whirling action before ejecting it from an orifice of the desired shape and size. The whirling motion is imparted to the liquid by passing it under pressure through a chamber of special construction. All of the nozzles of this type are inherently inefficient because of the pressure drop caused by the absorption of energy as fluid friction when the liquid traverses the nozzle chamber.

It is an object of the present invention to produce an atomizing nozzle of a design radically different from that discussed above in which energy losses due to fluid friction are in a large part eliminated.

It is a further object of this invention to produce an atomizing nozzle in which a much lower fluid pressure is required to obtain a certain degree of atomization than is the case with the presently-known types of atomizing nozzles.

It is still another object of the invention to provide an atomizing nozzle of relatively simple and compact construction which brings about a more efficient atomization of liquids than those presently in use.

Another and further object of the invention is to provide an atomizing nozzle which will operate efficiently and bring about a fine degree of atomization of a liquid by using only the force supplied by the liquid under pressure.

Other and further objects of the invention will be apparent from the detailed description thereof, taken in conjunction with the following drawings, in which:

Figure 1 of the drawing is a front elevational view, partly in cross-section, of the device of this invention in which atomization is effected by a vibrating orifice-containing resilient member.

Figure 2 is a front elevational view, partly in cross-section, of a modification of the device of Figure 1 in which the vibrating orifice-containing member is an integral part of the body portion of the device.

Referring with greater particularity to the device of Figure 1, numeral 4 designates a body portion of any desired shape, preferably cylind-

rical, having a chamber 6 therein, an inwardly flanged end section 7 forming a circular opening, and an internally threaded end section 8. Chamber 6 is preferably cylindrical and of circular cross-section; however, chamber 6 may be oval or polygonal in shape, if desired.

5 A flanged and hollow male plug 9 suitably threaded is fitted into threaded end section 8 of body portion 4. Plug 9 may be connected to body portion 4 by welding or may even constitute an integral part of body portion 4 such as when the nozzle is made by casting or molding in a suitable manner. Plug 9 contains a plurality of apertures 11 surrounding a central threaded aperture 12 in the end thereof. Apertures 11 and 12 openly communicate between chamber 6 and the hollow interior of plug 9. The juncture between plug 9 and body portion 4 may be sealed by means of a conventional circular gasket 13.

10 A threaded valve member 14 comprising a conically-shaped terminal portion 16 and an enlarged terminal portion 17 containing a groove or notch to receive a screw driver is screwed into aperture 12 of plug 9. When in position, the conically-shaped terminal section 16 of valve member 14 presses against an orifice-containing resilient member 18 and is seated in a cylindrical orifice 19 of circular cross-section in member 18. Member 18 is made of a circular disk of suitable 15 spring steel or other resilient material and orifice 19 is located centrally therein. Valve member 14 and orifice 19 are axially aligned and may be made of suitably hard material to resist erosion and wear, for example of hardened steel or alloy 20 known to those skilled in the art.

25 Valve member 14 is seated on the inner edge of orifice 19 to form a line or knife edge contact and urges the orifice-containing member 18 firmly against a conventional gasket 21 and flanged 30 end section 7 of body portion 4. Gasket 21 effectively seals the juncture between member 18 and body portion 4. Member 18 may be sealed to body portion 4 by welding or soldering without departing from the scope of this invention.

35 Hollow plug 9 is connected to a conduit 22 supplying liquid under pressure to chamber 6. Any suitable means may be employed to connect conduit 22 to the device of Figure 1, such as threading as shown, or soldering or welding, without departing from the scope of this invention. The various other parts of the device may be connected by the above methods, if desired.

40 In operation liquid under pressure passes from conduit 22 through apertures 11 to chamber 6 and thence through orifice 19. The size of orifice 45

19, the resiliency and mass of orifice-containing member 18, and the force with which valve member 14 presses against orifice 19 are so co-related to one another that the passage of liquid under pressure through orifice 19 supplies a force in correct phase relationship so that orifice-containing member 18 is maintained in forced vibration. The rapid vibration of the edge of orifice 19 upon the conically-shaped terminal portion 16 of valve member 14 breaks up the liquid passing through orifice 19 into a fine spray-like form.

Member 18 is preferably a circular disk between about $\frac{1}{64}$ and about $\frac{1}{4}$ of an inch thick but may be as thin as 0.01 of an inch. Orifice-containing member 18 acts like a spring.

In general the greater the mass of the vibrating member 18, the lower will be the frequency of vibration; and the greater the force with which valve member 14 presses against vibrating member 18, the higher will be the frequency of vibration. The frequency of vibration also tends to increase with an increase of liquid pressure at the source, but this factor is usually not as important as the mass of the vibrating member. Thus, it is seen that by varying and balancing the co-acting forces, the operable limits of the device may be widely changed and any desired degree of atomization can be procured. Depending on the above factors the frequency of vibration may vary between about 60 and several thousand cycles per second.

Figure 2 of the drawing illustrates a modification in which the orifice-containing member and vibrating member is an integral part of the body portion having a chamber 31 therein and an end section 32 containing an orifice 33 of circular cross-section. The opposite end of body portion 29 is internally and externally threaded at 34 and 39, respectively. End section 32 is usually relatively thin in comparison to other portions of body portion 29 so that it is slightly flexible when subjected to considerable force. Section 32 of the nozzle may be made of special alloys or of steel heat treated in a suitable manner to impart to it the desired hardness and resiliency.

As in the device of Figure 1, the device of Figure 2 has a male plug 36 suitably threaded to fit into the internally threaded section 34 of body portion 29. Plug 36 may be connected to body portion 29 by other conventional methods such as welding, bolting, etc., without departing from the scope of this invention. Plug 36 contains a plurality of apertures 37 surrounding a central threaded aperture 38.

A threaded valve member 41 comprising a conically-shaped terminal portion 43 and an enlarged terminal portion 42 is screwed into aperture 38 of plug 36. When in position in aperture 38, the conically-shaped terminal section 43 of valve member 41 presses against the inner edge of orifice 33 and is seated therein to make a knife edge contact therewith. Valve member 41 and orifice 33 are axially aligned. The force with which the end 32 and valve member 41 make contact is adjusted by screwing valve member 41 into aperture 38 of plug 36, or by adjusting the position of plug 36 itself.

Body portion 29 is connected to a conduit 44 supplying liquid under pressure to chamber 31, such as by threading as shown at 39. The liquid passes from conduit 44 through apertures 37 of plug 36 to chamber 31.

The arrangements of the elements of the device of Figure 2 obviate the necessity of any gaskets for sealing the various parts in order to pre-

vent leakage of liquid from the nozzle. Valve member 41 may be easily made an integral part of plug 36 by machining, casting or welding in a manner known to those skilled in the art.

5 When an integral part of plug 36, valve member 41 is adjusted by changing the position of plug 36.

The operation of the device of Figure 2 is similar to the device of Figure 1. Liquid under pressure passes from chamber 31 through orifice 33 and causes end section 32 to vibrate. The vibration of end section 32 breaks up the liquid from orifice 33 into a fine spray as the result of the vibration of the inner edge of orifice 33 against conically-shaped terminal portion 43 of valve member 41.

10 The thickness of end section 32 is between about $\frac{1}{64}$ and about $\frac{1}{4}$ of an inch for best results, but greater or lesser thicknesses may be used 20 without departing from the scope of this invention. End section 32 may be tapered slightly as shown:

The terminal portion of the valve member which fits into the orifice of the vibrating member of the device of Figures 1 and 2 may be spherical in shape without departing from the scope of this invention:

25 Preferably the included or apex angle formed by the conically-shaped portion of the valve head of the nozzles shown in Figures 1 and 2 is between 60 and about 150 degrees, the actual angle best suited for any particular valve head will depend on such factors as the size of the orifice and the pressure of the liquid being atomized. Included angles between 90 and 120 degrees for the valve head are preferred.

30 In operation, the potential energy available from the pressure of the liquid is consumed by the friction of the liquid passing through the nozzle and by the energy necessary to cause vibration of the orifice-containing member. For maximum efficiency, therefore, it is desirable to reduce the energy losses to a minimum. The greater the proportion of the total energy available for use in vibrating the orifice-containing member, the higher the frequency of vibration that can be obtained which results in the maximum dispersion of the liquid as a spray or fog for a given pressure. In fact, if energy losses 45 are too great the valve member will not vibrate. Accordingly, the dimensions and shapes of such elements as the orifice and the valve member are important and the following dimensions serve as a guide for the construction of a nozzle having minimum frictional losses. The diameter of the orifice should not be so small as to cause excessive energy losses by the passage of liquid therethrough. Generally, the diameter of the orifice will be between about $\frac{1}{64}$ and about $\frac{1}{2}$ inch, but larger or smaller diameter orifices may be used depending on such factors as the pressure of the liquids and the capacity of the nozzle. The diameter of the valve head is only slightly larger than the diameter of the mouth of the orifice in order to insure uniform particle size. Preferably, the diameter of the valve head is not more than $\frac{1}{32}$ of an inch larger than the diameter of the orifice. For example, a valve head not greater than $\frac{3}{32}$ of an inch in diameter should be used with an orifice $\frac{1}{16}$ of an inch in diameter.

55 The atomizing nozzles shown in Figures 1 and 2 may be used on liquids at various pressures. Best results are obtained at pressures above about 100 pounds per square inch gage and up to pressures as high as the tension of the orifice.

containing member correlated with the orifice diameter will permit. Pressures as high as 6000 pounds per square inch gage may be used with the vibrating type nozzle of this invention with excellent results characterized by high efficiency. For maximum capacities and finest sprays, pressures between 1000 and 6000 pounds per square inch gage are preferred for the nozzles shown but lesser pressures can be used at sacrifice of capacity and fine dispersion.

Various alterations and modifications of the nozzle illustrated, such as the size and shape of the orifice and the orifice-containing member, may become apparent to those skilled in the art without departing from the scope of this invention. Various uses of the nozzle and its principle of operation are contemplated such as for the use in humidification, emulsification, milk spraying, spray drying, fuel injection, spray painting, powder metallurgy, surface cooling, fire extinguishing distillation, etc. The vibrating principle of the nozzle in atomizing liquids has its obvious application as an integral part of equipment and appliances, such as, oil burners, internal combustion engines, fire extinguishers, etc. In any of these instances the nozzle portion of the apparatus is defined by the various associated parts necessary to produce a vibrating action of the orifice-containing member, the result of which vibrating action liquid is atomized.

It is understood that the essence of the present invention is the employment of a vibrating orifice-containing member, whether a separable or integral portion of the nozzle, for atomizing of a liquid, and it is realized that there are many available ways other than those specifically disclosed herein for bringing about the desired results.

Having described my invention, I claim:

An atomizing nozzle comprising a metallic body portion having a chamber within said body

portion and an outlet orifice of circular cross section of $\frac{1}{64}$ to $\frac{1}{2}$ of an inch in diameter and smaller than said chamber in one end of said body portion, the other end of said body portion being threaded internally and externally, the orifice-containing end of said body portion being resilient and 0.01 to $\frac{1}{4}$ of an inch in thickness, a perforated plug threaded and positioned in said threaded end of said internally threaded portion of said body portion and adapted to receive a threaded valve member, a stationary valve member positioned in said threaded plug and having a conically shaped terminal portion of circular cross section of not greater than about $\frac{3}{2}$ of an inch in diameter greater than said orifice and having a conically shaped terminal portion pressing against the edge of said orifice, and said valve member having an apex angle between about 60° and about 150° and terminating adjacent said outlet orifice.
